Primary Examiner—Kay H. Chin

Attorney, Agent, or Firm—Gerald E. Helget; Rider, Bennett,
Egan & Arundel[57] **CLAIM**The ornamental design for a hollow boat fender, as shown
and described.**DESCRIPTION**FIG. 1 is a side elevational view of a hollow boat fender
showing my new design in an environmental scene in
phantom outline;

FIG. 2 is a side elevational view;

FIG. 3 is a top plan view taken along lines 4—4 of FIG. 2;
FIG. 4 is a cross-sectional view and taken along lines 4—4 of
FIG. 2; and,

FIG. 5 is a perspective view.

No claim is made to the dock and boat shown in phantom
outline for environmental purposes only.**1 Claim, 2 Drawing Sheets**Fig. 1.→ 4

Fig. 2.Fig. 3

Fig. 4.

Fig. 5.
